UNITED STATES PATENT OFFICE

ADRIAN R. APPLE, OF GLENDALE, CALIFORNIA, ASSIGNOR TO WALLACE CHINA COMPANY, LTD., OF HUNTINGTON PARK, CALIFORNIA, A CORPORATION OF CALIFORNIA

DESIGN FOR A PLATE OR SIMILAR ARTICLE

Application filed August 8, 1932. Serial No. 44,551. Term of patent 7 years.

To all whom it may concern:

Be it known that I, ADRIAN R. APPLE, a citizen of the United States, residing at Glendale, in the county of Los Angeles and State of California, have invented a new, original, and ornamental Design for a Plate or Similar Article, of which the following is a specification, reference being had to the accompanying drawing, forming a part hereof and in which

Fig. 1 is a plan view of a plate, showing

my new design. It is understood that the ornamentation shown is continued throughout the border of the plate as indicated in broken lines.

Fig. 2 is a fragmentary view of the plate shown in Fig. 1, showing the design to enlarged scale.

I claim:

The ornamental design for a plate or similar article, as shown and described.

ADRIAN R. APPLE.
